US0D1024571S

(12) **United States Design Patent** (10) **Patent No.:** **US D1,024,571 S**
(45) **Date of Patent:** **** Apr. 30, 2024**

(54) **ORAL CARE IMPLEMENT**

- (71) Applicant: **Colgate-Palmolive Company**, New York, NY (US)
- (72) Inventors: **Fan Gang Xie**, Shanghai (CN); **Yanmei Ji**, Jiangsu (CN); **Wen Jin Xi**, Shanghai (CN)
- (73) Assignee: **Colgate-Palmolive Company**, New York, NY (US)
- (**) Term: **15 Years**

(21) Appl. No.: **29/843,083**

(22) Filed: **Jun. 17, 2022**

(51) LOC (14) Cl. **04-02**

(52) U.S. Cl.

USPC **D4/104; D4/110**

(58) **Field of Classification Search**

USPC D4/100, 101, 104, 105, 106, 110, 130, D4/132, 136, 138, 199; D24/176

(57) **CLAIM**

The ornamental design for an oral care implement, as shown and described.

DESCRIPTION

FIG. 1 is a front perspective view of an oral care implement showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof; and,

FIG. 8 is an enlarged bottom view thereof.

The broken lines illustrate portions of the oral care implement that form no part of the claimed design.

1 Claim, 4 Drawing Sheets
